DESIGN FOR A LIGHTING FIXTURE

Clarence A. Godshalk, Ardmore, Pa., assignor to Godshalk Company, Philadelphia, Pa., a corporation of Pennsylvania

Application April 13, 1936, Serial No. 62,106

Term of patent 7 years

To all whom it may concern:

Be it known that I, Clarence A. Godshalk, a citizen of the United States, residing at Ardmore, in the county of Montgomery and State of Pennsylvania, have invented a new, original, and ornamental Design for Lighting Fixtures, of which the following is a specification, reference being had to the accompanying drawing, forming part thereof.

ture, showing my new design, the dominant feature being shown in solid lines.

I claim:

The ornamental design for a lighting fixture as shown and described.

In testimony whereof I have hereunto signed my name.

CLARENCE A. GODSHALK.
